UNITED STATES PATENT OFFICE

PAUL NAEHER, OF CHICAGO, ILLINOIS, ASSIGNOR TO B. F. GUMP CO., OF CHICAGO, ILLINOIS, A CORPORATION OF ILLINOIS

AUTOMATIC DELIVERY MECHANISM

Application filed May 24, 1929. Serial No. 365,634.

This invention relates to an automatic delivery mechanism primarily designed for use in connection with packing conveyors but adapted for other uses.

The main object of this invention is to provide an automatic delivery mechanism which is set in operation by the weight of the article placed thereon for delivering the article to a desired point. In the illustrated embodiment of the invention, the article is shown as delivered to a traveling conveyor and on account of the automatic feature of the delivery mechanism, the operator is enabled to work at any speed he desires without having to gauge the time.

The invention comprises the novel structure and combination of parts hereinafter described and more particularly pointed out and defined in the appended claims.

In the accompanying drawings which illustrate a preferred form of this invention and in which similar reference numerals refer to similar features in the different views:

Figure 1 is a central vertical sectional view taken through a packing conveyor and the delivery mechanism involving this invention.

Figure 2 is an enlarged sectional view taken upon the line II—II of Figure 1.

Figure 3 is an enlarged sectional view taken upon the line III—III of Figure 1.

Figure 4 is an enlarged sectional view taken through the automatic delivery mechanism involving this invention.

The invention in its broadest aspect consists of a delivery mechanism which is set in motion by the weight of the article placed thereon and which automatically returns to its normal position as soon as the article is removed therefrom. In the present embodiment of this invention, this delivery mechanism is adapted to deliver bags to a traveling packing conveyor which is shown upon the left hand side of the drawings in Figure 1. This packing conveyor is old and well known in the art and only a brief description thereof is necessary.

Referring to Figure 1, it will be noted that the packing conveyor consists of an endless belt 1 which travels around the pulleys 17, 2, 3 and 4. The left hand end of the belt

and pulley are not shown. The belt 1 travels between the walls 18 as shown in Figure 2. These walls are connected to a base which is in turn connected to the operating mechanism of the machine whereby the walls are rocked as the bags pass therebetween for the purpose of settling the contents in the bags. However, as this does not involve any part of this invention it has not been fully illustrated. Beneath the conveyor 1, there is a motor 5 which is geared by sprocket gearing 6 to a shaft 7. Shaft 7 carries a gear 8 which meshes with a gear 9 secured to a shaft 10. It might be mentioned that the walls 18 are connected with the shafts 7 and 10 for rocking movement. The shaft 7 through the instrumentality of a gear 11 drives a gear 12 on a shaft 13. The shaft 13 carries a small beveled pinion 14 which in turn drives a beveled gear 15 secured upon a shaft 16. This shaft 16 is geared by sprocket gearing 19 to the left hand pulley for the conveyor 1 whereby motion is imparted to the conveyor 1.

The apparatus involving this invention is designed for delivering packages or articles to the conveyor 1. This apparatus consists of a stand 20 which is provided at its upper end with laterally inwardly directed ledges 21 and upstanding flanges 22 which form seats and attaching means for the side walls 23 of the casing. The ends of the stand are provided with inwardly directed flanges 24 upon which the side walls 23 also rest as shown in Figure 4. At intermediate points the side walls 23 are connected by braces 25. A support 26 which consists of a narrow strip is secured to the top of the braces or brackets 25. An endless chain 27 has its upper reach traveling over said support to prevent sagging thereof. This endless chain 27 is provided with spaced impelling spurs 28 and is adapted to be rotated around terminal sprockets 29 which are adapted to be secured on suitable shafts journaled in the walls 23 of the casing in any approved manner.

A pair of three armed levers 30 are pivoted to the walls 23 of the casing as indicated at 31 in Figure 4. The levers 30 have arms

30a which project forwardly of the pivot point 31 and these forwardly projecting arms are pivoted to depending lugs 32 upon a rising and falling platform 33. The levers 30 have also rearwardly directed arms 30b which extend rearwardly from the pivot point 31. These rearwardly directed arms 30b have depending arms 34 pivotally connected thereto and between the lower ends of the arms 34 there is secured a counterweight 35. The levers 30 also have depending arms 30c which extend downwardly approximately from the pivot point 31. The lower ends of the arms 30c are connected to the forward end of links 36 which extend in horizontal direction to the rear end of the casing. The rear ends of the links 36 are pivoted to the lower arms of bell crank levers 37 which are pivoted at their apices to the side walls of the casing 23 as indicated at 38. The upper arms of the bell crank levers 37 extend in horizontal direction toward the front end of the casing and are pivoted to the rising and falling platform 33 as indicated at 39.

The rising and falling platform 33 is provided with upwardly diverging guide members 40 as shown in Figure 3. A slide or plunger 41 provided with upwardly diverging grooves for receiving the guide members 40 is supported upon the platform. A casing member 42 is attached to the slide 41 and the forward end of this casing member is in the form of a vertical abutment 43 which is adapted for engaging the bags and shifting them to the conveyor 1 as will later more fully appear.

Mechanism has been provided for connecting the slide 41 with the endless chain 27 when a filled bag has been deposited upon the forward end of the rising and falling platform 33 which it will be noted projects forwardly of the bag engaging abutment 43. This mechanism has a certain amount of lost motion before the slide 41 is actuated in order to allow any drippings from the hopper to fall into the bag upon the platform. In the illustrated embodiment of this invention, this mechanism comprises a slide block 44 which is slidably dovetailed in the slide plate 41. In other words, the slide block 44 has a slidable interlocking relation with the slide 41. The slide block 44 has a depending abutment 45 which is adapted to be engaged by a spur 28 on the endless chain whereby the slide block 44 may be propelled in a forward direction. Upon the upper surface of the slide block 44 there is secured an abutment 46 which is adapted to travel between a forward abutment 47 and a rear abutment 48 carried by the slide 41. With reference to Figure 4, it will be noted that the slide block 44 will travel a certain distance before the abutment 46 will engage the abutment 47 and propel the slide 44 in a forward direction. This lost motion will

allow plenty of time for the drippings in the hopper to drop into the bag on the platform before it is shifted upon the conveyor 1. This lost motion interval may be varied by moving the abutment 47 forwardly or rearwardly. To this end the abutment 47 is adjustably secured by means of removable screws. A coiled leaf spring 49 is mounted upon the rear part of the casing that encloses the endless chain 27 and this leaf spring is connected with the slide 44 for retracting the same. The leaf spring 49 is adapted for retracting the slide block 44 and the slide 41 when the same have been elevated after a bag has been delivered to the conveyor 1. The rearward movement of the slide block 44 and the slide 41 is limited by a rubber stop member 50 which is secured to the rear end of the rising and falling platform 33.

The forward end of the rising and falling platform 33 which receives the bags or articles to be delivered is provided with suitable slots forming a sort of grid in order to allow spillings to fall therethrough. To intercept the spillings a suitable receptacle 51 is placed therebeneath. The aforementioned stand 20 is provided with suitable means for supporting the receptacle 51.

The endless sprocket chain 27 is adapted to be continuously driven by the packing conveyor. To this end suitable sprocket gearing 52 connects the forward sprocket 29 with the rear sprocket 17 of the packing conveyor. This sprocket gearing 52 is so designed that speed of the chain 27 will substantially equal that of the packing conveyor 1 in order that the bag may be delivered to the conveyor 1 at the same speed that the conveyor 1 is traveling.

In the drawings, there is shown a feed hopper 53 beneath which the bag that is adapted to be filled may be held by the operator. When this bag is filled or substantially filled, the operator will allow the same to fall upon the platform 33. As soon as the bag is deposited upon the platform 33, the delivery mechanism will automatically be set in motion for delivering the bag to the packing conveyor 1. Consequently the operator may work at any speed he desires since the operation of the delivery mechanism is not governed by any timed elements.

In the operation of the apparatus before described, the weight of the bag or article upon the platform 33 will cause the same to descend and actuate the levers 30. The actuation of the levers 30 will cause the rear levers 37 to be actuated and as the levers 37 are connected to the rising and falling platform, it will be lowered until the abutment 45 is located in the path of the impellers 28 on the chain 27. As the chain 27 is constantly revolving an impeller 28 will engage the rear surface of the abutment 45 and slide the block 44 in a forward direction. The

slide block 44 will move forwardly a certain amount before it actuates the slide plunger 41 and during this time an opportunity will be afforded for any drippings or leavings in the hopper 53 to drop into the bag. When the slide block 44 has moved forwardly a sufficient distance for taking the abutment 46 into engagement with the abutment 47, the slide plunger will be carried along with the slide block 44 in a forward direction with the result that the vertical abutment 43 will engage the bag upon the forward end of the platform 33 and shift the same therefrom to the traveling conveyor 1 at the same speed that said traveling conveyor is moving. As soon as the article or bag is ejected from the platform 33, the platform 33 will immediately rise due to the action of the counterweight 35. It will be realized, that when the platform 33 descends the counterweight arms 34 will swing in an upward direction with the arms 30b of said lever. Of course it will be realized that the weight of the package or bag should be sufficient to overcome the effect of the counterweight 35 which is designed for normally holding the different parts in balance. When the bag is ejected from the platform 33 and the weight 35 is descending two levers 30 and 37 will be actuated for elevating the slide block 44 together with the slide plunger and platform for the purpose of removing the abutment 45 from the path of the chain impellers 28. At about this same time the spring 49 will be effective for retracting the slide bar 44. The slide bar 44 will first be retracted without moving the slide plunger 41 due to the lost motion existing between the abutments 47 and 48. When the slide block 44 has been retracted until the abutment 46 engages the rear stop 48, the slide plunger will be retracted into the position shown in Figure 4. At the rearward movement of the slide block 44, it will engage the rubber abutment 50 which acts as a stop to limit further rearward movement. In this position the delivery mechanism is set for receiving another bag for delivery to the packing conveyor.

It will be appreciated that the machine or delivery mechanism does not depend upon any time element but may be operated according to the wishes of the operator by merely depositing a bag upon the platform 33. The apparatus is automatic in that it requires no particular attention nor adjustment nor operation by levers or the like to set the same in motion.

I am aware that many changes may be made and numerous details of construction may be varied through a wide range without departing from the principles of this invention, and I, therefore, do not purpose limiting the patent granted hereon otherwise than necessitated by the prior art.

I claim as my invention:

1. In an apparatus of the class described, an upwardly and downwardly movable platform, a plunger slidably mounted upon said platform, driving mechanism for said plunger including a member having relative movement with respect to said plunger and means for controlling said driving mechanism through the raising and lowering of said platform.

2. In an apparatus of the class described, an upwardly and downwardly movable platform adapted for receiving an article thereon, a plunger for ejecting the article from said platform, an endless member beneath said platform, said endless member having driving impellers, an actuator for said plunger having an abutment adapted for engagement with an impeller upon the lowering of said platform and a lost motion connection between said actuator and plunger.

3. The combination with a traveling conveyor, of a delivery mechanism for supplying articles to said conveyor comprising an endless member having the same rate of speed as said conveyor, a plunger normally disengaged from said endless member and means for operatively connecting said plunger and endless member when an article is deposited upon said delivery mechanism.

4. The combination with a conveyor, of delivery mechanism for supplying articles to said conveyor at the same rate of travel as said conveyor including an endless member and a plunger embodying a slidably depending member normally disengaged from said endless member but adapted for effecting a driving relation with said endless member when an article is deposited upon said delivery mechanism.

5. In a delivery mechanism of the class described, a platform adapted for receiving an article thereon, a plunger for ejecting the article from said platform, an endless driving member beneath said platform, an actuator for operating said plunger and normally out of engagement with said endless member, means whereby said platform and plunger descend when an article is deposited on said platform for effecting an engagement between said actuator and endless member, and means for elevating said platform and plunger when said article is ejected from said platform.

6. In a delivery mechanism, a pair of parallel side walls, a pair of levers pivoted to said side walls, a link for connecting said levers, a platform adapted for receiving articles pivoted to said levers, a counterweight carried by one of said levers for normally holding said platform in elevated position, a slidably plunger carried by said platform, said slidably plunger having spaced abutments, an actuator slidably mounted on said plunger and having an abutment located be-

5. Between said two abutments, an endless driving element mounted beneath said platform, said actuator having an abutment normally out of driving relation with said endless member but adapted to be brought into operative relation therewith upon a lowering of said platform, and yielding means connected to said actuator for retracting the same to initial position.

10. 7. In a delivery mechanism of the class described, a platform adapted for receiving an article thereon, a plunger for ejecting the article therefrom, means including a counterweight for normally holding said platform in an elevated position, an actuator for operating said plunger, an endless driving member beneath said actuator and normally out of driving relation therewith, said platform being adapted to be lowered when an article 15 is placed thereon to bring said actuator in operative relation with said endless driving member, an said counterweight being adapted for elevating said platform to bring said actuator out of driving relation with said 20 endless member when the article is ejected from said platform, and means for retracting said actuator and plunger when said platform has been elevated.

30. 8. In a delivery mechanism of the class described, a platform adapted for receiving articles thereon, means for supporting said platform for lowering and elevating movement including a counterweight for normally holding said platform in elevated position, 35 an article ejecting plunger slidably mounted upon said platform, and driving mechanism for said plunger engageable upon a lowering of said platform and disengageable upon the elevation of said platform and means for automatically retracting said plunger upon the elevation of said platform.

40. 9. In a delivery mechanism of the class described, a platform adapted for receiving an article thereon, interconnected levers for sustaining said platform for lowering and elevating movement, a counterweight connected to one of said levers for normally holding said platform in elevated position, said counterweight being overbalanced by the article placed thereon for causing a lowering of said platform, an ejecting plunger slidably mounted upon said platform, a slidable actuator carried by said plunger, an endless driving member beneath said platform, said actuator and driving member being adapted for coming into operative relation upon the lowering of said platform and being disengageable upon the elevation of said platform, and said counterweight being effective for elevating said platform when the article has been ejected therefrom.

45. 10. In a delivery mechanism of the class described, a platform, means for supporting said platform for a lowering and elevating movement, means for normally holding said

platform in elevated position, said last mentioned means being adapted to be overcome by the weight of an article placed upon said platform for lowering the same, a slideable ejector mounted upon said platform, and operating means for said ejector adapted to actuate said ejector upon the lowering of said platform, and render it ineffective upon the elevation of said platform and means for retracting said ejector upon the elevation of said platform.

11. In an apparatus of the class described, a platform adapted for receiving articles thereon, levers for supporting said platform for lowering and elevating movements, a device for ejecting articles from said platform, an endless member, and impellers on said endless member for actuating said device when said platform is lowered.

12. The combination with a belt conveyor, of delivery mechanism, for feeding articles to said conveyor comprising an endless member having substantially the same rate of speed as said belt conveyor, a platform above said endless member for receiving articles thereon, means for supporting said platform for lowering and elevating movements, a device for ejecting the articles from said platform to said belt conveyor, and means on said endless member for actuating said device upon the lowering of said platform.

In testimony whereof I have hereunto subscribed my name at Chicago, Cook County, Illinois.

PAUL NAEHER.
